UNITED STATES PATENT OFFICE

CONRAD B. MAURER AND HOWARD P. MAURER, OF PHILADELPHIA, PENNSYLVANIA

SCENIC DISPLAY DEVICE

Application filed February 18, 1929. Serial No. 340,716.

This invention relates to scenic display devices which may be used in store windows, homes, and other places, particularly at Christmas time, and has more especial relation to a device of this kind in which the scenic display includes a mountain effect and a water fall effect.

One of the leading objects of the present invention is to employ a rigid support movable through which is a belt symbolic of a water fall, and to completely surround the supporting structure for the belt with mountain scenery paper such as is disclosed in our U. S. Letters Patent No. 1,483,466, dated Feb. 12, 1924; and Patent No. 1,650,372, dated November 22, 1927.

A further object of the present invention is to provide a belt symbolic of a water fall which is comprised of a canvas or like endless band having secured thereto upon its face a silver cloth loosely attached at intervals so that in the rotation of the endless band the effect of moving water is obtained.

A still further object of the present invention is to provide a structure of the character stated in which incandescent lamps are carried by the structure symbolic of the mountain for throwing rays of light upon the moving band symbolic of the water fall.

A still further object of the present invention is to provide a motor for operating the endless band and lights for displaying rays of light upon the water fall effect, all of said parts being in electrical connection for attachment to a conventional lighting socket.

Other and further objects reside in the provision of general details of construction and in the arrangement and combination of parts for attaining the results sought by the foregoing objects.

The invention consists of the novel construction hereinafter described and finally claimed.

The nature, characteristic features and scope of the invention will be more fully understood from the following description taken in connection with the accompanying drawings forming part hereof, and in which:

Fig. 1, is a view in elevation of a display

device embodying the invention with the mountain scenery disclosed in full lines.

Fig. 2, is a rear view of Fig. 1, the mountain scenery, however, being arranged in dotted lines more clearly to illustrate the operating mechanism.

Fig. 3, is a view in side elevation of Fig. 2.

Fig. 4, is a fragmentary face view of the endless belt shown in the foregoing Figs.

Fig. 5, is a vertical sectional view of Fig. 4.

For the purpose of illustrating our invention we have shown in the accompanying drawings one form thereof which is at present preferred by us, since the same has been found in practice to give satisfactory and reliable results, although it is to be understood that the various instrumentalities of which our invention consists can be variously arranged and organized and that our invention is not limited to the precise arrangement and organization of the instrumentalities as herein shown and described.

Referring to the drawings, and with more especial relation now to Figs. 2 and 3, the reference numeral 1 designates a base, usually of wood, rising from which is a pair of fixed standards 2, said standards being connected at their top by a cross piece 3. In practice these parts are also usually made of wood. Journalled in the standards 2 adjacent the top thereof is a shaft 4 having fixed thereto a roller or cylinder 5 of relatively large diameter and having a roughened circumference. In practice sand paper or equivalent material is used for the purpose. Extended across the lower portions of the standards 2 is a cross bar 6 for guiding the lower end of an endless band or belt 7 as operated by the roughened surface of roller or cylinder 5. The shaft 4 is driven from electrical motor 8 by means of a belt 9 cooperating with a wheel 10 upon shaft 4.

Viewed from the rear as in Fig. 2 the standards 2 and operating mechanism are exposed, but as viewed from the front and side as shown in Figs. 1 and 3 the operating mechanism with the exception of the water fall effect is concealed by mountain scenery 11. This mountain scenery is formed of specially prepared paper such as is described in our

Letters Patent Nos. 1,483,466 and 1,650,372, and it is believed that a description thereof is unnecessary in this case. The mountain scenery paper 11 is crumpled and arranged upon the base 1 and standards 2 so that viewed from the front all that one sees is an elongated opening designated 12 through which the moving endless band 7 may be observed. The sides of the display device, of course, are completely covered with the paper 11.

In order to provide a good effect, a plurality of incandescent lamps 13 are used, best seen in Fig. 3, for displaying light rays upon the moving belt 7 when the motor is running, it being understood that the lights 13 are upon the same circuit operating the motor and that current may be supplied from a conventional lighting socket by means of a plug 14.

In perfecting our water fall effect we employ for the endless belt or band 7 a piece of canvas, or similar textile material which is relatively soft and pliable and attach to the face thereof silver fabric 8, which fabric presents a silver, sparkling-like effect. We have found in practice that instead of gluing or otherwise securing the entire surface of the silver fabric 8 to the belt 7, good results are obtained by leaving at intervals, preferably irregular intervals, loose portions 14, see Fig. 5. These loose portions have the tendency to flatten out and again re-assert themselves in the operation of the endless belt 7 which may be termed a collapsing and expanding structure. With the rotation of the endless band this collapsing and expanding of the loose portions 14 of the silver cloth produces the effect of moving water and with the endless band viewed only through the elongated opening as shown in Fig. 1, a very realistic water fall scene is produced.

While we have described our invention as being especially applicable for use in connection with mountain scenery paper as embodied in our aforesaid patents, we wish it understood that scenery in imitation of other subjects may be employed and material other than said mountain scenery may be employed. We also wish it understood that while primarily our device has been designed in small size, for use around the Christmas holidays in Christmas gardens and the like, we may also greatly increase the size of the device so as to be employed for commercial purposes, as for instance, advertising purposes.

Having thus described our invention, what we claim as new is:

60. 1. A device of the character stated comprising a base, a pair of standards rising therefrom, a shaft provided with a roughened surface rotatable between said standards, means for driving said shaft, mountain scenery arranged around the front and sides of

said standards with an elongated open space at the front of the device, and an endless belt of pliable fabric, a textile material as silver cloth secured to one face of said belt throughout its entire length but loosely applied at intervals to provide an effect symbolic of a water fall during belt operation.

2. As a new article of manufacture an endless belt of pliable fabric, a textile material of silver cloth secured to one face of said belt throughout its entire length, but loosely applied at intervals to provide an effect symbolic of a water fall during belt operation.
